UNITED STATES PATENT OFFICE.

HOUSTON M. CARROLL, SR., OF SAN ANTONIO, TEXAS.

FLASK CLAMP.

Application filed November 29, 1927. Serial No. 236,499.

The device forming the subject matter of this application is a clamp for a flask of the kind used by dentists in the making of false teeth. The invention aims to provide a novel form of clamp which can be operated by the manipulation of a single screw. Another object of the invention is to provide a clamp which will hold the parts of the flask together with a resilient action, thereby insuring a firm clamping together of the parts of the flask. Another object of the invention is to provide a clamp of the sort specified which may be used on flasks of known construction, without making changes in the flask, it being unnecessary for a dentist to cast away his supply of flasks in order that he may take advantage of the clamp that forms the subject matter of this invention.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the drawings:—

Figure 1 shows in side elevation, a device constructed in accordance with the invention;

Figure 2 is a top plan;

Figure 3 is a vertical transverse section;

Figure 4 is a side elevation wherein parts are broken away.

The device forming the subject matter of this application is adapted to be used with flasks of different sorts, but primarily with a flask of known form, the same including a body, denoted generally by the numeral 1.

The body 1 of the flask comprises a cup-shaped base 2 upon which rests a removable intermediate member or ring 3, surmounted by a lid 4 having internal depending projections 5 which engage within the intermediate member 3 to hold the lid and the intermediate member together against relative lateral movement.

The base 2 of the flask has an outstanding front lug 6 provided with an opening 7. On the intermediate member 3 there are parallel wings 8 located above the lug 6 on the base

2. In addition to the lug 6, which may be denominated a first lug, the base 2 has rear or second lugs 9, provided with openings 10 and with slots 12, the slots 12 forming seats 60 in which are received, depending fingers 14 on the intermediate member 3, to prevent relative lateral shifting between the intermediate member 3 and the base 2. The intermediate member 3 has wings 11 that are located above 65 the lugs 9.

The flask above described is of known construction, and no novelty is claimed for it, saving in so far as it may enter into combination with parts hereinafter described.

The clamp is a composite structure and includes a main member 15 embodying a metal cross bar 16 into which a screw 17 is threaded, the screw constituting a pressure member, and having in its outer end, a socket 18 adapted to receive a tool (not shown) whereby the screw is rotated. The clamp includes a frame made of resilient material, the diverging arms 19 of the frame being extended through the cross bar 16. The arms 19 are bowed slightly, as shown at 26 in Figure 3, to enhance the resiliency of the clamp. The arms 19 are connected by an end piece 20 on which is pivoted a latch 21, in the form of a U-shaped bail, the eyes 22 of the latch or bail being mounted on the end piece 20. The arms 19 are provided at their remote ends with rectangularly disposed fingers 23 arranged approximately parallel to each other and terminating in angular extensions 24 located approximately parallel to the arms 19, the extensions 24 terminating in upstanding knobs 25 which are disposed about parallel to the fingers 23.

In practical operation, the clamp is mounted in place with the fingers 23 extending down behind the wings 11 and behind the lugs 9, as shown in Figure 4, the knobs 25 extending upwardly into the openings 10 of the lugs 9, and the arms 19 and the cross bar 16 being located above the lid 4, as clearly shown in Figures 1, 2 and 3 of the drawings. The bail or latch 21 is swung downwardly until it extends around the wings 8 on the intermediate member 3, and beneath the first lug 6 on the base 2. The screw 17 then is rotated and fed downwardly until it bears upon the lid 4, and the parts 2-3-4 of the flask will be held securely together, especially in view of the fact that the arms 19 have some resiliency.

Heretofore it has been the custom to hold

the parts of the flask together by three separate instrumentalities mounted in the several openings 7-10. One object of the present invention, therefore, is that the parts of the flask may be held together by a single instrumentality, and through the manipulation of a single movable element, to wit, the screw 17. It is to be observed that the extensions 24 of Figure 4 engage with the lugs 9 on the base 2, the bail-shaped latch 21 cooperating with the lug 6 and with the wings 8. Another advantage of the present invention, therefore, is that it may be used on flasks of a standard and known form, without working any changes in the flask. Finally, the general structural features of the clamp, including the resilient arms 19 and the single screw 17, make a better article than those which have preceded it.

20 What is claimed is:-

1. A clamp for molding flasks, comprising a main member provided at one end with angularly disposed fingers that are spaced apart transversely and provided with means 25 for engaging the lugs on a flask, a lug-en-

gaging latch pivoted to the opposite end of the main member, and a pressure device operating in the intermediate portion of the main member.

2. A clamp for molding flasks, comprising a resilient frame including arms connected at one extremity by an end piece, the arms being provided at the opposite extremity with angularly disposed fingers provided with means for engaging the lugs on a flask, 35 a flask-engaging latch pivoted to the end piece, a pressure member, and means for mounting the pressure member on the intermediate portions of the arms.

3. A clamp for molding flasks, including a cross bar, a U-shaped frame the side portions of which are mounted on the cross bar, the side portions of the frame being supplied at one end with flask-engaging hooks, a flask-engaging latch pivoted to the opposite end 40 of the frame, and a pressure device movable in the cross bar.

In testimony that I claim the foregoing as my own, I have hereto affixed my signature.

HOUSTON M. CARROLL, SR.
